UNITED STATES PATENT OFFICE.

SARKIS H. BOYAJIAN, OF MELROSE, MASSACHUSETTS.

ARCH-SUPPORTER FOR BOOTS AND SHOES.

1,242,317.

Specification of Letters Patent.

Patented Oct. 9, 1917.

Application filed July 25, 1917. Serial No. 182,657.

To all whom it may concern:

Be it known that I, SARKIS H. BOYAJIAN, a citizen of the United States, residing at Melrose, county of Middlesex, State of 5 Massachusetts, have invented a certain new and useful Improvement in Arch-Supporters for Boots and Shoes, of which the following is a specification, reference being had therein to the accompanying drawings.

10 Arch supporters as heretofore constructed for boots and shoes have not been quickly and easily adjustable by the wearer to the shape of the instep. Heretofore, such arch supporters have usually been made from a 15 cast of the foot, in which case they are expensive, or have been made in accordance with a certain standard shape and size, in which cases they fit the foot imperfectly. In either case, they are likely to do injury 20 to the shoes. I am aware that it has been proposed to make an adjustable arch supporter, but such supporters have not been adjustable without taking the shoe apart and doing injury to it, or they have been 25 on the exterior of the boot or shoe so as to be likely to catch and trip the wearer and are therefore dangerous and unsightly.

My invention has for its object a new and improved arch supporter, in combination 30 with the shoe itself, which, although made into the shoe, is capable of ready adjustment by the wearer for the purpose of increasing or diminishing the amount of curvature given the shaft of the shoe. The 35 device embodying my invention is simple and inexpensive; it is not visible from the outside of the shoe and therefore does not disfigure the shoe at all. It is easily accessible in case adjustment of the arch is required. This adjustment may be made by 40 the wearer himself.

The invention will be fully understood by reference to the following description taken in connection with the accompanying drawings, and the novel features thereof are distinctly defined in the claims at the close of 45 this specification.

In the drawings, Figure 1 is a longitudinal section of a shoe containing an arch 50 supporter embodying my invention.

Fig. 2 is a sectional view taken on line 2—2 of Fig. 1.

Fig. 3 is a longitudinal section of a heel embodying my invention.

Fig. 4 is a side elevation of the front member.

Referring to the drawings, at A is indicated the upper of a boot or shoe, the heel being shown at B, the outsole at C and insole at D. The shoe may be made of any desired type and may or may not have a metal shank. It is only necessary that the shoe be of such a construction that the arch supporter can be inserted between the two layers of the instep, preferably between the 65 outsole and the insole.

At 11 is shown the front member and at 12 is shown the rear member of a device by means of which the curvature of the instep of the shoe is regulated. The front member 11 consists of a relatively flat flexible plate secured in any suitable manner as by 70 nails 13 to the sole of the shoe and a stem 14 which is screw threaded at the rear end. The heel member 12 includes a lug 18 which 75 extends downwardly from the heel seat into a suitable recess 15 in the upper part of the heel of the shoe. This lug 18 may be carried on the under side of the plate 16 or may be otherwise suitably secured to the 80 rear part of the shoe. The lug 18 is bored out as shown at 17 to admit the screw 85 threaded stem 14 and a tubular nut 19 having an enlarged head. Several holes 20 are drilled radially in the head of the said nut 19 so that the nut can be turned by inserting a pin into one of the holes. Similar holes 30 are also drilled in the front end of the stem. The insole of the shoe D has a recess or opening 21 formed therein adjacent a corresponding recess 22 in the plate 16 so that access may be had through these recesses to the holes 20 in the nut. If desired the recess 22 in the plate 16 may be closed by the insertion of a small piece 90 of leather of corresponding size and shape. At 31 is a hole in the sole through which the front end of the tubular nut 19 may be reached and the nut turned to adjust the 95 curvature without taking off the shoe.

If more than normal curvature of the shank of the shoe adjacent the instep of the wearer is required the nut 19 is turned as described so that it screws onto the stem 14 and tends to bring the two ends closer together. Since the device lies nearer the center of curvature, it tends to bend the instep 100 of the shoe and increase its curvature. The 105

materials of which this portion of the shoe are made are ordinarily of sufficient strength so that when held in place by the tension member, as just described, the curvature 5 will be maintained.

Ordinarily when the shoes containing the arch support are first worn, the support will be adjusted so that the shank is relatively flat, and as the wearer becomes accustomed 10 to them, the curvature will be increased from time to time as required. In this way, the shoe may be adjusted to the foot of the wearer until it fits perfectly and the wearer does not have to go through a period of dis- 15 comfort or even of pain in getting accustomed to the supports. Another important feature is the fact that the instep does not rest directly on a metal surface which is substantially rigid. It is, therefore, more 20 comfortable and better for the foot. As the device lies wholly between the insole and the outsole, it does not detract from the appearance of the shoe, nor in fact is it visible, nor is there any danger of tripping resulting from it. 25

What I claim is:

1. In combination with a boot or shoe, having a plurality of layers of material at the shank, a tension member lying between 30 said layers of material and secured at its ends to the shoe, and means for shortening said tension member to increase the curvature of the adjacent portion of the boot or shoe.

2. In combination with a boot or shoe, having an insole and an outsole, a tension 35

member lying between said insole and outsole, and secured at its ends to the shoe, and means for shortening said tension member to increase the curvature of the adjacent 40 portion of the boot or shoe.

3. In combination with a boot or shoe having an insole and an outsole, an arch adjusting device lying between said insole and outsole and comprising a thin flexible 45 front member secured to the shoe forwardly of the shank, a rear portion secured to the shoe adjacent the heel, and screw actuated means for varying the distance between said members. 50

4. The combination with a boot or shoe having an insole and an outsole, a tension member secured at its ends to the shoe and located between the insole and the outsole, and screw actuated means for shortening 55 said tension member there being an opening in the insole adjacent said screw actuated means to permit access thereto.

5. The combination with a boot or shoe having an insole and an outsole, a tension 60 device comprising a front member secured to the shoe forwardly of the shank, a rear member having a depending lug, said rear member being secured to the shoe to the rear of the shank, said forward member having 65 a screw threaded stem received within said lug, and a nut on said stem, there being an opening through the insole to permit access to the said nut.

In testimony whereof I affix my signature. 70

SARKIS H. BOYAJIAN.
